Des. 191,301
Patented Sept. 12, 1961

191,301

OBSERVATION TOWER OR SIMILAR ARTICLE

John K. Groseclose, Columbus, Ohio, assignor to Dresser
Industries, Inc., Dallas, Tex., a corporation of Delaware

Filed Mar. 2, 1961, Ser. No. 64,116

Term of patent 14 years

(Cl. D13—1)

FIG. 1

FIG. 4

FIG 1 is a front elevational view of an observation tower or similar article showing my new design;
FIG. 2 is a side elevational view;
FIG. 3 is a top plan view; and
FIG. 4 is a perspective view thereof.

I claim:
The ornamental design for an observation tower or similar article, substantially as shown.
